A. BLATTSTEIN.
CASTING MACHINE.
APPLICATION FILED JULY 28, 1914.

1,124,841.

Patented Jan. 12, 1915.

UNITED STATES PATENT OFFICE.

ADOLPHE BLATTSTEIN, OF NEW YORK, N. Y.

CASTING-MACHINE.

1,124,841.

Specification of Letters Patent.

Patented Jan. 12, 1915.

Application filed July 28, 1914. Serial No. 853,682.

To all whom it may concern:

Be it known that I, ADOLPHE BLATTSTEIN, a subject of the King of Roumania, residing at New York, in the county of New York and 5 State of New York, have invented new and useful Improvements in Casting-Machines, of which the following is a specification.

The general object of this invention is to dispense with the cumbersome and expensive apparatus at present employed for effecting the introduction of molten metal into a flask or mold in the operation of making gold, or other metallic, inlays for cavities in teeth, by substituting therefor 10 an apparatus designed for holding the molten metal and the mold and susceptible of being operated by hand and in such manner as to effect the introduction of the molten metal into the mold by centrifugal 15 force. And to these ends the invention resides in providing a holder for the mold and adapting this holder to be readily rotated in a circle when held by hand.

Other objects will appear and be better 20 understood from that embodiment of my invention of which the following is a specification, reference being had to the accompanying drawings, forming part hereof, in which:—

30 Figure 1, is a contracted side elevation partly in section of the casting machine. Fig. 2, is a detail side elevation partly in section of one end of a modified form of machine. Fig. 3, is a detail side view of one end of a further modified form of machine. Fig. 4, is a side elevation showing the pattern supported by the flask cover. Fig. 5, is a side elevation of a cluster of inlays or castings.

40 In proceeding to make an inlay or casting in accordance with the principle of my invention the cavity of the tooth is treated or prepared in the ordinary manner after which a pattern or impression of the cavity is made by introducing thereto, and in the well known manner, a quantity of dentist's wax, sufficient to substantially fill the cavity. The wax is then withdrawn by a peel, usually in the form of a needle, which is adapted upon being introduced into the wax to

attach or otherwise interlock itself therewith so that the wax will be withdrawn from the cavity upon pulling the peel outwardly. By thus proceeding a pattern of the cavity of the tooth is had and this pattern is impinged on one end of the peel. Novelty is not claimed for the proceeding thus far described since the essence of the present invention resides in the device for obtaining the casting of the pattern just mentioned.

In adapting my invention to be used in connection with the hereinbefore stated pattern I provide a flask, a cover for the flask, and a holder for the flask which holder may 55 be readily rotated in a circle when held in the hand. The flask is by preference formed of metal and may have any desired contour. Its volume will be such as to admit of its containing a pattern, or a plurality of these, when arranged therein in the form of a cluster or in any other convenient arrangement, and a quantity of plaster-of-Paris or any of the equivalents of this material used by dentists in making molds. 75

The cover of the flask is provided with a boss or protuberance in its inner face which serves as a former. This former functions to make a dished depression in the upper surface of the plaster mold when the cover is placed upon the flask and the latter filled with plaster-of-Paris. The provision of a dished depression in the plaster mold prevents the molten metal from flowing over the sides of the flask during the operation 80 of melting the metal. The cover is also provided with a socket or sockets into which the free end or ends of the peel may be inserted. Thus, the cover functions as a support for the pattern during the well known 85 operation of applying a coating of plaster-of-Paris to the pattern.

The flask holder is adapted to be connected to the flask, and either before or after the effecting of this connection, the 95 molten metal is placed into the mold, so that while the metal is in a melted condition it will by the action of centrifugal force, be forced into the mold upon rotating the device.

In the embodiment shown the flask holder is indicated generally by *a*, the flask by *b*, and the flask-cover by *c*. In the form shown in Fig. 1, the flask holder *a* comprises 5 a ring 5 which is pivotally attached by screws 6 or their equivalents and at diametrically opposite points, to the arms 7-7 of a yoke formed of stout steel wire or its equivalent. The upper ends of the arms of 10 this yoke are suitably connected to a shank 8, as by a nut 9 into one end of which the arms 7-7 are fitted and into the other end of which the shanks 8 is screwed or otherwise secured.

15 The shank 8 is pivotally connected to the handle 10 which in the embodiment shown is arranged at an angle (preferably at right angle) to the shank 8. For convenience in mounting, the end of the shank 8 may be 20 provided with an eye 11, through which passes a headed spindle 12, which is fastened in the handle 10.

The flask *b* is an open ended hollow cylindrical structure of a size to nicely fit 25 within the basket 13, formed integral with, or otherwise suitably connected to the ring 5. The basket has an internal shoulder 14 which forms a support for the flask *b*, and the bottom of the basket below the shoulder 30 14 is provided with openings 15. The flask *b* is internally provided with a circular groove 16, which provides a means for permitting the plaster-of-Paris introduced in a soft state into the flask to interlock there- 35 with, whereby the plaster mold will be prevented from falling or longitudinal displacement in the flask. The cover *c* is provided with a flange 17, which bears on the edge of the flask when the cover is arranged 40 as shown in Figs. 1 and 3, and the opening 18 in the protuberance 19 of the cover is usually filled with wax or its equivalent so as to retain the peel when the latter is introduced thereinto as indicated in Fig. 4.

45 With the form shown in Fig. 2, the basket 13 of Fig. 1 is eliminated and is substituted with the flask 20 the upper end of which has a stepped flange 21, which bears upon the corresponding shaped inner surface of 50 the ring 22 when the flask is arranged in the ring, as will be obvious. The yoke, a fragment of which is shown in Fig. 2, corresponds to the yoke shown in Fig. 1, and the pivotal connection 23, between the yoke and 55 the ring is preserved as described for Fig. 1.

The flask shown in Fig. 2, differs from that shown in Fig. 1, in that it combines the flask and the basket structures, shown in the latter figure, that is to say, it is bottomed 60 as indicated by 24, and this bottom has openings as indicated by 25. The cover 26 for the form shown in Fig. 2, corresponds to the cover 17, previously described, ex-

cept that it has a stepped flange to accommodate the stepped flange 21 of the flask 20. 65

With the form shown in Fig. 3, the yoke 27, has a loose connection with the shank 28, so as to permit of the shank being held at an angle to the yoke. In this connection 70 the flask *c* is removable from the basket as described in connection with the form shown in Fig. 1. The basket 29 has openings 30

in the bottom thereof which correspond to the openings 15 and 25 in Figs. 1 and 2 re- 75 spectively. In using any form of machine just described, a pattern as shown in Fig. 5 is provided. Now, with the flask detached

from the holder and arranged upright on a table, the pattern is inserted into the flask and the operator holding the peel keeps the 80 pattern suspended a trifle above the lower edge of the flask. Plaster-of-Paris in a plastic condition is then introduced into the flask and around the pattern. The quantity of plaster-of-Paris used is sufficient to ap- 85

proximately fill the flask, after which the cover is positioned on the flask and forced downwardly into the plaster-of-Paris so as to form the dished upper end previously 90 mentioned. Upon removing the cover, the end of the peel will be visible in the plaster and when the plaster is substantially set, the peel may be withdrawn with a tweezer. When a single peel is used it is inserted in the opening 18 of the cover *C* as indicated 95 in Fig. 4 after the plaster of Paris has been placed in the flask and when the cover is applied to the flask the pattern and peel are forced into the plaster.

The withdrawal of the peel leaves open- 100 ings extending from the dished upper end of the plaster down to the pattern. The pat- 105 tern is then melted out of the plaster in the usual manner. Thus when the metal is placed into the dished upper end of the plaster mold and the flask placed in the holder and the latter given several rotations by holding the handle 10 in the hand 110 the force which tends to move the metal from the flask by the rotation of the holder, will effect the introduction of the molten metal into the openings left by the peel in the plaster and into the mold, so that after 115 the device has been brought to rest, and sufficient time allowed for the same to cool, perfect castings will be found upon breaking open the plaster mold. The castings thus produced will have attached to them metallic threads. In using the castings the threads will provide handles for adjusting 120 the castings to the cavities of the teeth. It will be understood that after the adjusting of the castings to the cavities, or before, if so desired, the threads may be detached.

The purpose of providing the holder with 125 a flexible connection is that when the shank

is held in a horizontal position, the axis of the ring and the flask contained therein, may extend vertically.

What I claim as new is:—

- 5 1. A casting device comprising a holder, a ring attached thereto, a flask detachably mounted in the ring, and a cover having a central protuberance detachably mounted on the flask.
- 10 2. A casting device comprising a holder,

a ring pivotally connected thereto, a flask detachably mounted in the ring, and a cover having a central protuberance detachably mounted on the flask.

In testimony whereof I affix my signature 15
in presence of two witnesses.

ADOLPHE BLATTSTEIN.
